US0D1088452S

(12) **United States Design Patent** (10) **Patent No.:** **US D1,088,452 S**
(45) **Date of Patent:** **** Aug. 19, 2025**

(54) **FOOTWEAR**

(71) Applicant: **Crocs, Inc.**, Broomfield, CO (US)

(72) Inventor: **Alexander Jacob Mayhew**, Denver, CO (US)

(73) Assignee: **Crocs, Inc.**, Broomfield, CO (US)

(**) Term: **15 Years**

(21) Appl. No.: **29/771,660**

(22) Filed: **Feb. 24, 2021**

Related U.S. Application Data

(63) Continuation of application No. 29/771,369, filed on Feb. 22, 2021.

(51) **LOC (15) Cl.** **02-04**

(52) **U.S. Cl.**

USPC **D2/947**; D2/954; D2/923

(58) **Field of Classification Search**

USPC D2/896, 902, 903, 907, 908, 913, 916, D2/918, 919, 922–924, 926, 939, 942, D2/943, 946, 947, 951, 953, 954, D2/956–960, 969, 970, 972–974

CPC A43B 13/12; A43B 13/122; A43B 13/125; A43B 13/127; A43B 13/14; A43B 13/141; A43B 13/143; A43B 13/00; A43B 13/02; A43B 13/023; A43B 13/026; A43B 13/04; A43B 13/08; A43B 13/10; A43B 13/16; A43B 13/18; A43B 13/181; A43B 13/187; A43B 13/189; A43B 13/20; A43B 13/22; A43B 13/24; A43B 13/28; A43B 13/30; A43B 13/32; A43B 13/34; A43B 13/36; A43B 13/223; A43B 3/12; A43B 3/126; A43B 3/0036

(57)

CLAIM

The ornamental design for footwear as shown and described.

DESCRIPTION

FIG. 1 is a front perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1–7 that are overlaid with a white transparent mask bounded by broken lines represent portions that form no part of the claimed design.

1 Claim, 7 Drawing Sheets
